UNITED STATES PATENT OFFICE.

OSCAR HANDLER, OF NEW YORK, N. Y.

ELECTRIC CONTROL FOR TAXIMETERS.

Application filed March 17, 1925. Serial No. 16,247.

This invention relates to electric controls for taximeters, an object of the invention being to provide means whereby the mechanism of the meter will be caused to operate 5 as soon as a passenger is seated in the cab even though the chauffeur fails to throw the signal arm to starting position. In other words, the broad object of my invention is to prevent fraud; that is to say, with my 10 improvements installed in a taxicab the chauffeur cannot convey passengers without registering on the meter.

Another object of the invention is the provision of mechanism which will ensure 15 that the meter will register, even though the usual controlling flag is not advanced or turned down, provided a passenger occupies the vehicle, the principal effect of this movement of the flag being to connect the 20 registering mechanism with the mechanism which advances or drives it.

It is a well known fact that dishonest chauffeurs make special rates with passengers and drive their taxis without operating the 25 meters so that the company owning the cab is defrauded. It is, therefore, the purpose of my invention to provide automatic means which prevent this fraudulent practice and which will result in a saving to the company 30 of fares, which have heretofore been lost.

With these and other objects in view, the invention consists in certain novel features of construction and combinations and arrangements of parts, which will be more fully 35 hereinafter described and pointed out in the claims.

In the accompanying drawings—

Figure 1 is a view in elevation showing my improved invention diagrammatically as 40 applied to a taxicab and a taxicab meter;

Figure 2 is a fragmentary view in sectional elevation illustrating my improved attachment or that portion thereof which is associated with the meter;

Figure 3 is a view in horizontal section 45 on the line 3—3 of Figure 2;

Figure 4 is a fragmentary view similar to Figure 3, showing the parts in a different position.

50 1 represents a taxicab and 2 a meter such as is commonly employed in registering fares. It is to be understood that my invention is to be applied to the standard type of meter and hence it is not necessary to describe the meter in detail except as to such

parts as are directly associated with my attachment.

All meters of this type are provided with clock mechanism, indicated diagrammatically by the reference numeral 3, and this 60 clock mechanism is held normally out of operation by a crank arm 4 which engages a sliding member 5 and is connected to a crank shaft 6 mounted in the frame 7' of the clockwork mechanism. 65

It will be understood that by the term "clock mechanism" is meant the operative parts of a taximeter which impart movement to register wheels to indicate the fare to be paid, and that this mechanism is ordinarily thrown into and out of operation by the movement of the flag. 70

This shaft 6 is capable of longitudinal as well as rotary movement and is provided with a crank arm 7 and with a coil spring 75 8 connected to the crank arm and functioning to turn the crank arm and shaft a predetermined distance and also functioning to hold the shaft 6 in a given longitudinal position. 80

Meters of the standard type are provided with a disk 9 fixed to a shaft 10 on which a signal arm 11 carrying the usual flag 11' is secured and located outside of the meter casing. When this signal arm is vertical 85 and the flag thrown up the meter is not operating, but when it is thrown down to a horizontal position it automatically functions to start or permit the clockwork mechanism to operate as a clock and also to operate the driving mechanism of the register or meter. This is due to the fact that the disk 9 is provided with a pin 12 which when the meter is not operating engages the arm 7 and holds the parts in the position indicated. 95

When this arm 11 is swung downwardly and to the right of Figure 2, the turning movement of the disk 9 moves the pin 12 in a direction which will allow the arm 7 to swing, hence permitting the shaft 6 to turn 100 so as to move the arm 4 in a direction to allow the slide 5 to lift and cause or permit the clock mechanism to start.

The parts above described constitute standard equipment of taximeters, and in conjunction with these parts I employ an improved attachment, which will be hereinafter described, to cause the clock mechanism to automatically start or be released by the entrance of a passenger into the cab. 105

It is of course to be understood that I do not limit myself to the specific construction and arrangement illustrated, but I have shown for the purpose a fixed contact 13 adapted to be engaged by a movable contact 14 on the seat 15 within the cab, so that when a passenger occupies the seat a circuit will be closed through the contacts 13 and 14 to operate my improved attachment, as 10 will be explained.

On the outside of the meter I secure a frame 16 which is preferably enclosed within a casing 17 so as to protect the mechanism from fraudulent manipulation as well as 15 from dirt and foreign matter.

This frame 16 supports a pair or any desired number of electromagnets 18 which control the position of a pivoted armature 19 normally held away from the magnets by a 20 spring 20. 21 represents a lever which is pivotally mounted on a short shaft 22 supported within the meter casing, and said lever projects at one end through an opening 23 in the meter casing, and into the casing 17. A coil spring 24 exerts pressure on one end of this lever 21, holding the same against the end of shaft 6 and causing said shaft to move longitudinally when the lever 21 is permitted a pivotal movement in one 30 direction.

The lever is, however, held against such pivotal movement by a trigger 25 pivotally mounted in the frame 16. This trigger has a finger 26 normally engaging the lug 27 35 on the end of lever 21, and said trigger also has a finger 28 which is held in a pivoted tripper 29 also mounted in the frame 16. This tripper 29 is of somewhat V-shape so that it accommodates the finger 28 between 40 a member 30 and a member 31 located at an acute angle to each other.

The tripper 29 has a crank arm 32 which is normally in engagement with a lug 33 on the armature 19. A coil spring 34 is positioned around a pin 35 secured to the frame 16. One end of this spring 34 bears against the trigger 25 while the other end bears against the fixed frame.

It will be noted that the arm 32 has a 50 recess 36 therein through which the lug 33 may be positioned when the armature 19 is attracted by the magnets 18, but in normal position this lug prevents a release of the set parts as above explained.

The lever 21 above referred to is formed at its inner end with a cam face 37 which is adapted to be engaged by a plate 38 secured to the disk 9 when said disk is moved to a predetermined position.

Within the meter casing I locate a pair 60 of electric contacts 39 and 40 mounted on a suitable support 41. These contacts may be of spring metal so that they are normally together, as indicated clearly in Figures 2 and 3.

A pin 42 on the disk 9 is adapted when the disk is moved in one direction to engage the contact 39 and force it away from contact 40 to open the circuit, as will be hereinafter explained. 70

A simple form of electric circuit which may be employed in connection with my attachment is illustrated diagrammatically in Figure 1. 42' represents a battery or source of electricity, which is connected at one side 75 by a wire 43 with contact 14. The other side of this battery is connected by a wire 44 with one of the magnets 18, the latter being in series and connected by a wire 45 with the contact 39. The contact 40 is connected by a wire 46 with the contact 13, but as the contacts 13 and 14 are normally apart the circuit is normally open. 80

The operation is as follows:

When a passenger enters the cab and rests 85 upon the seat 15, the contact 14 will move against the contact 13 to close the circuit above described. If the chauffeur is honest and has moved the signal arm 11 to horizontal position to start the meter, the disk 9 90 will have turned to a position to bring the pin 42 far enough to move contact 39 away from contact 40 and thus open the electric circuit, and the meter will operate as intended without any interference on the part 95 of my improved attachment.

If, however, the chauffeur is not honest and does not swing the signal arm 11 to operate the meter, my improved mechanism 100 will operate as follows:

The spring 24 is the source of movement of the trigger 25 and tripper 29 when release is effected by the electro-magnets. The spring 34 has apparently a resetting function and works in opposition to spring 105 24. The trigger 25 is in continual engagement with the lever 21, and when the parts are in the position shown in Figure 3 the effect of spring 24 is to press the arm 32 against the lug 33. When this lug is withdrawn by movement of the armature, the spring 24 tilts the trigger and the tripper into the position shown in Figure 4, compressing the spring 34, and by the movement 110 of the lever 21 starting the clock mechanism. When the lever 21 is restored to normal position by the cam 38 actuated by the flag, the spring 34 returns both trigger 25 and tripper 29 to the normal position shown 115 in Figure 3. The spring 24 will then force the inner end of the lever 21 in a direction to move the shaft 6 longitudinally a distance sufficient to free the arm 7 from the pin 12. The spring 8 will then turn the shaft, causing the arm 4 to release the starting slide 5 of the clock mechanism and the meter will function so as to register the fare and defeat the dishonest intention of the chauffeur. 120

If the chauffeur concludes to operate his 125

meter at any time, a downward movement of the arm 11 will cause the disk 9 to turn, the plate 38 will move to a position to engage the cam face 37 of lever 21, causing the latter to swing in a direction to compress the spring 24 and permit the shaft 6 to move longitudinally to normal position so that when the disk 9 is returned to its normal position, the pin 12 will engage arm 7 and turn shaft 6 in a direction to stop the clock mechanism.

When a passenger rises from the seat, the circuit will be opened so that the armature 19 will be moved by its spring in its normal direction so as to hold the parts against accidental release, as above explained.

While I have illustrated what I believe to be a preferred embodiment of my invention it is obvious that various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement and electric means for releasing the lever.

2. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement, electric means for releasing the lever, said lever having a cam face, and a plate on the disk adapted to engage the cam face and return the lever to normal position.

3. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement, a pair of contacts, a pin on said disk adapted to separate said contacts when the disk is manually moved, and electromagnets controlling the release of the lever

and included in a circuit with a source of supply and with said contacts.

4. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement, said lever having a cam face, a plate on the disk adapted to engage the cam face and return the lever to normal position, a pair of contacts, a pin on said disk adapted to separate said contacts when the disk is manually moved, and electromagnets controlling the release of the lever and included in a circuit with a source of supply and with said contacts.

5. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement, a pair of contacts, a pin on said disk adapted to separate said contacts when the disk is manually moved, electromagnets controlling the release of the lever and included in a circuit with a source of supply and with said contacts, a taxicab supporting the parts above described, and a pair of normally separated contacts adapted to be closed by pressure on the seat of the cab, said contacts included in said circuit and normally spaced apart.

6. The combination with a taximeter having a controlling arm, a disk fixed to move with the arm, a clock mechanism, and means normally holding the clock mechanism out of operation, of a lever pivotally mounted between its ends, a spring exerting pressure against the lever tending to move the same in a direction to release the clock mechanism, means normally holding the lever against movement, said lever having a cam face, a plate on the disk adapted to engage the cam face and return the lever to normal position, a pair of contacts, a pin on said disk adapted to separate said contacts when the disk is manually moved, electromagnets controlling the release of the lever and included in a circuit with a source of supply and with said contacts, a taxicab supporting the parts above described, and a pair of normally separated contacts adapted to be closed by pressure on the seat of the cab, said contacts included in said circuit and normally spaced apart.
